Primary Examiner — Dominic Simone(74) *Attorney, Agent, or Firm* — Sterne, Kessler, Goldstein & Fox P.L.C.(57) **CLAIM**

The ornamental design for a portion of a shoe, as shown and described.

DESCRIPTION

FIG. 1 is a bottom plan view of a portion of a shoe showing my new design; and,

FIG. 2 is a side view thereof.

The broken lines in the Figures show environment for illustrative purposes only and form no part of the claimed design. The dot-dashed lines in the Figures show an indeterminate border around portions of the subject matter being claimed.
